UNITED STATES PATENT OFFICE

111,910

DESIGN FOR A PUTTING GAME DEVICE

Fred W. Preece, Toledo, Ohio

Application March 14, 1938, Serial No. 75,792

Term of patent 3½ years

To all whom it may concern:

Be it known that I, Fred W. Preece, a citizen of the United States, residing at the city of Toledo, in the county of Lucas and State of Ohio, have invented a new, original, and ornamental Design for Putting Game Device, of which the following is a specification, reference being had to the accompanying drawings, forming a part thereof.

Fig. 1 is a front and side perspective view of a putting game device, showing my new design; and

Fig. 2 is a front and opposite side perspective view thereof.

The back of the device is plain and unornamented.

I claim:

The ornamental design for a putting game device, as shown and described.

FRED W. PREECE.
